UNITED STATES PATENT OFFICE.

CORNELIUS O. WESTBY, OF RENVILLE, MINNESOTA.

IMPLEMENT FOR PLACING AND CLINCHING SPLIT RIVETS.

Application filed March 27, 1922. Serial No. 547,238.

To all whom it may concern:

Be it known that I, CORNELIUS O. WESTBY, a citizen of the United States, residing at Renville, in the county of Renville and 5 State of Minnesota, have invented certain new and useful Improvements in Implements for Placing and Clinching Split Rivets; and I do declare the following to be a full, clear, and exact description of the invention, such as will enable others skilled in 10 the art to which it appertains to make and use the same.

This invention relates to an improved implement for placing and clinching split rivets and one object of the invention is to provide an implement of the character described which will resemble a pair of pliers and which will be so constructed that the rivets may be held in engagement with one 15 jaw of the pliers and then forced through the material which it is desired to rivet and the prongs of the rivet slightly spread so that the pliers may be shifted for a final clinching without the rivet tending to slip 20 out of place.

Another object of the invention is to so construct this device that the rivet may be prevented from accidentally slipping out of engagement with the implement before being 25 forced through the material to be riveted while at the same time permitting the implement to be easily moved out of engagement with the rivet after the rivet is placed.

Another object of the invention is to so construct this implement that the anvil carried by one jaw which serves to spread and clinch the rivet will be set up above the plane of the upper face of the jaw so that 30 the portion of the material through which the rivet passes may be very firmly clamped and the rivet thus caused to be clinched in a very efficient manner.

This invention is illustrated in the accompanying drawings, wherein:

Figure 1 is a perspective view of the improved rivet placing and clinching device.

Figure 2 is also a perspective view but looking at the device from a different angle.

Figure 3 is a sectional view showing the device being made use of to place a rivet.

Figure 4 is a view similar to Fig. 3 showing the device in use for clinching the rivet which has previously been placed, as shown 55 in Fig. 3.

This improved rivet placing and clinch-

ing device resembles a pair of pliers and is provided with the two jaws 1 and 2 having handle extensions 3 and 4 which are pivotally connected as shown at 5 so that by 60 moving the handles after the manner of a pair of pliers, the jaws may be moved towards and away from each other. If desired, one of the handles may be provided with a tack puller 6 and the other may have 65 its end portion formed similar to a screw-driver as shown at 7, this end portion 7 being used either as a screw-driver or as means for prying up the prongs of a split rivet so that the head of the rivet may be 70 engaged by the tack puller and the rivet removed. The jaw 1 is provided at its outer end with a head or block 6 and intermediate its length is provided with a clinching arm 7' which is somewhat longer than the block 75 6 and provides not only means for clinching the rivet as will be hereinafter brought out but also provides a stop limiting the extent to which the block may be moved towards the jaw 2. A strip 8 which is formed of 80 resilient material is secured against the side of the outer end portion of the jaw 1 and extends along one side of the block as shown in Fig. 3 and has its free end portion bent to extend in spaced relation to the end of 85 the block. This free end portion of the rivet carrier is provided with a slot 9 so that the rivet 10 may be engaged by this carrier and held as shown in Fig. 3. From an inspection of this figure, it will be readily 90 seen that after the rivet has been placed, the jaws may be moved apart slightly and then moved transversely so that the clip or carrier 8 will be moved out of engagement with the rivet. Anvil forming blocks 11 and 12 95' are provided upon the jaw 2 beneath the head 6 and clinching arm 7' and each has its upper face shaped to provide a longitudinally extending rib 13 and transversely curved side portions thus providing each of 100 the anvils with a centrally disposed spreading rib and cam surfaces so that the prongs of the rivet may be spread and curled longitudinally when inserted and firmly clinched in place.

When this device is in use, the two strips 14 and 15 which are to be riveted together will be placed one upon the other and the rivet 10 will then be put in place with its head between the block 6 and free end of 110 the carrier strip 8 and its shank portion which will be in the form of prongs ex-

tending through the slot 9. This device may be used for placing rivets in any material which it is desired to secure but it will be assumed that the strip 14 is a brake band and that the strip 15 is a brake band lining. After the rivet has been put in place, the brake band and lining will be positioned between the block 6 and anvil 11 and the handles 3 and 4 will be moved towards each other thus causing the jaws to be brought toward each other and thereby causing the shank of the rivet to be forced through the band and lining. This rivet will of course be put in place as shown in Fig. 3 so that as the shank portion of the rivet passes through the two strips 14 and 15, the spreading rib 13 of the anvil 11 will move between the free ends of the prongs of the rivet and cause these prongs to be moved apart to such an extent that the rivets cannot pass back through the openings formed in the two strips. The jaws of the device can then be moved apart slightly and moved transversely so that the rivet passes out of the slot 9 and is left in place. The device will then move forwardly a sufficient distance to bring the end of the clinching arm 7 in engagement with the head of the rivet and the spread end portions of the prongs upon the anvil 12. The handles of the device will then be grasped and tightly gripped so that the rivet will be moved longitudinally with the spreading rib of the anvil 12 moving the prongs of the rivet apart and the curved side portions of the anvil causing the prongs to be curled and finally positioned for entering the under strip 15 which in the present case will be a brake band lining. Further gripping of the handles 3 and 4 will cause the rivet to be firmly clinched in place. It should be noted that since the anvil 12 extends above the face of the jaw 2 that the portion of the strips 14 and 15 through which the rivet passes will be compressed and therefore the rivet can be very tightly clinched in place and relatively embedded in the strips 14 and 15. After the rivet has been firmly clinched in place, the device can be removed and a second rivet put in place or the device put away until again needed. When it is desired to remove a rivet, it is simply necessary to pry the clinched end portions of the prongs outwardly by means of the tapered end 7 of the handle 3 and then engage the

head of the rivet by means of the end portion 6 of the handle 4 and draw the rivet out. There has thus been provided a device for applying and clinching rivets which will be easy to use and very efficient in operation. If desired a spring 16 may be provided to normally hold the handles apart and permit easy operation of the device.

I claim:

1. A rivet placing and clinching device comprising jaws movable towards and away from each other, one jaw having a placing anvil and a clinching anvil and the other having a placing head and a clinching arm, the clinching arm being engageable with the clinching anvil and preventing movement of the placing head into contact with the placing anvil, and means for releasably holding a rivet in position between the placing head and anvil with its head engageable by the placing head and its shank engageable by the placing anvil for preliminary upsetting after passing through material to be riveted.

2. The structure of claim 1 having the placing anvil provided with a rib for spreading the end portions of prongs forming the shank of the rivet and concaved faces at opposite sides of the spreading rib for directing the prongs in flaring curves after being separated.

3. The structure of claim 1 having the clinching anvil provided with a rib for extending between spread end portions of prongs forming the shank of the rivet and having concaved faces upon opposite sides of the rib for causing the prongs to be curved longitudinally and their ends embedded in the material being riveted during clinching.

4. The structure of claim 1 having the placing anvil provided with means for spreading the free end portions of prongs forming the shank of the rivet and the clinching anvil provided with means for continuing spreading of the prongs during clinching.

5. The structure of claim 1 having the rivet holding means consisting of a strip extending beneath the placing head and having a rivet receiving recess.

In testimony whereof I have hereunto set my hand.

CORNELIUS O. WESTBY.
